US0D1053458S

(12) **United States Design Patent** (10) **Patent No.:** **US D1,053,458 S**
(45) **Date of Patent:** **** Dec. 3, 2024**

(54) **EYELASH TWEEZERS**

(71) Applicant: **QINGDAO JIAHE YONGRUN BEAUTY TECHNOLOGY CO., LTD.**, Shandong (CN)

(72) Inventor: **Chao Yu**, Shandong (CN)

(73) Assignee: **QINGDAO JIAHE YONGRUN BEAUTY TECHNOLOGY CO., LTD.**, Shandong (CN)

(**) Term: **15 Years**

(21) Appl. No.: **29/842,783**

(22) Filed: **Jun. 15, 2022**

(51) LOC (14) Cl. **28-03**

(52) U.S. Cl.

USPC **D28/55**
